UNITED STATES PATENT OFFICE.

KARL NACKE, OF BROOKLYN, NEW YORK, ASSIGNOR TO UNITED METAL SPINNING CO., OF BROOKLYN, NEW YORK, A CORPORATION OF NEW YORK.

DESIGN FOR A HUSK FOR BALL-LAMP-SOCKET COVER FOR LIGHTING FIXTURES.

Application filed May 19, 1922. Serial No. 2,313. Term of patent 3½ years.

To all whom it may concern:

Be it known that I, KARL NACKE, a citizen of the United States, and residing at Brooklyn, in the county of Kings and State of New York, have invented a new, original, and ornamental Design for a Husk for Ball-Lamp-Socket Cover for Lighting Fixtures, of which the following is a specification, reference being had to the accompanying drawing, forming part thereof.

Fig. 1 is a top view of a husk for ball lamp socket cover for lighting fixtures, showing my new design;

Fig. 2 is a side view of the same.

I claim—

The ornamental design for a husk for ball lamp socket cover for lighting fixtures, as shown.

KARL NACKE.
